UNITED STATES PATENT OFFICE.

SAMUEL T. DAVIDSON, OF ST. LOUIS, MISSOURI.

OIL BURNER.

Application filed July 28, 1924. Serial No. 728,633.

This invention relates to oil burners.

An object of the invention is to provide an oil burner comprising a base frame of strong and preferably integral construction 5 permitting the passage of air to the burner head supported below a combined vapor tube and baffle plate designed and arranged to control the quantity, direction and velocity of the air drawn by the suction created 10 by the combustion at the combined generator and flame spreader.

Another object of the invention is to provide an oil burner including an integrally cast generator and flame spreader having a 15 burner head of novel and improved construction that will prevent the formation of carbon, in combination with a combined vapor tube and baffle plate supported above the burner head and below the generator and 20 flame spreader to control the air and to permit the flame to contact with the generator and flame spreader and with the inlet and outlet passages thereof, thus applying heat at three points and increasing the operating 25 efficiency with the result that cleaner and better combustion is obtained.

Another object of the invention is to provide an improved oil burner possessing all 30 of the advantages and novel features of construction herein mentioned or apparent from the following description, reference being made to the drawing showing a preferred embodiment of the invention and in which—

Fig. 1 is a plan view showing two burners 35 upon a single base.

Fig. 2 is a side elevation thereof.

Fig. 3 is an end elevation.

Fig. 4 is a vertical sectional view of one 40 of the burners.

Fig. 5 is an enlarged longitudinal sectional view of the burner head.

While I have shown two burners mounted upon a single base it will be understood that the number of burners mounted upon a base 45 or in adjacent relationship may be varied as desired. As shown the base casting is in the form of an integral frame comprising side members 1 connected by end members 2, and in case more than one burner is mounted upon a base connected intermediate 50 of the ends by cross connections 3. If desired, the sides, ends and cross connections of the frame, or any of them, may be provided with inside flanges 4, and the cross connections 3 may be united by a relatively 55 wide horizontal connection 5. Notches 6

may be formed in the lower edges of the sides and ends of the base casting, those in the sides being opposite the cross connections 3 in a structure in which more than one 60 burner is mounted upon a single base. The part of the base casting directly under each burner is formed with a generating cup or tray 7 designed and adapted to contain a quantity of oil for initial combustion to 65 vaporize the oil at the burner head. The oil passing from the burner head then becomes ignited and heats the combined generator and flame spreader and continues to generate gas until the supply of oil passing thereto 70 is discontinued.

A supply pipe 8 for each burner is connected with the lower end of a passage 9 forming an integral part of the base frame. A pipe section 10 leads from the upper end 75 of each passage 9 and supports a combined generator and flame spreader and cooperating parts.

The combined generator and flame spreader comprises an integral casting including 80 a well 11, an inlet 12 connected with the pipe 10, and a downwardly extending outlet 13 having a laterally extended extremity 14.

The burner head comprises a number of 85 parts assembled as a unit and is removably connected to the outlet passage 13 to facilitate replacement without involving the expense of a new generator. The design of the burner head is such as to facilitate removal of any foreign matter introduced with the 90 fuel and can be easily taken apart for inspection and cleaning. As shown the assembly 95 comprises the tubular part 15 screwed into the lateral extension 14 of the outlet from the generator. The passage 16 in the part 15 is much smaller than the opening 100 through the outlet passage 13 and has one or more lateral openings 17. The restricted area of the passages 16 and 17 as compared with the openings through the outlet 13 increases the speed of the gas vapor passing 105 to the vapor tube, with the result that the deposit of a carbon formation is reduced to a minimum. The portion of the tubular part 15 in which the openings 17 are formed 110 is enclosed in a non-metallic jacket 18 preferably composed of mineral steatite, heated until it becomes characterized by a degree of hardness that is nearly impossible to cut. The ends of the jacket are sealed by packing 19 and the parts are held in assembly by a nut 20 screwed onto the end of the part 15.

An orifice 21 is formed through the upper wall of the jacket 18, preferably of smaller area than the openings 16 and 17, thereby further increasing the speed of the gas vapor 5 toward the generator. The orifice 21 is in vertical alinement with the center of the lower wall of the generator 11.

10 A combined vapor tube and baffle plate is supported by projections 22, integral with the inlet and outlet passages of the generator. Said tube and baffle plate is composed of two parts each comprising a horizontal baffle portion 23 and a vertical half tube portion 24, the edges of which contact when 15 assembled. One of the plates 23 has on each end a grooved portion 25 and the other of said plates has on each end a flange 26 engaging the corresponding grooved portion 25 thereby securing said parts in position. 20

In operation oil is admitted under pressure. A quantity of oil in the generating cup is ignited and supplies the initial heat to vaporize the oil in the burner head. The vapor gas passing through the orifice 21 rises through the vapor tube 24 with increased speed due to the reduced area of the orifice 21 and the openings leading thereto from the outlet 13. The baffle plate 23 serves as an obstacle to prevent air from rising to the flame from underneath the generator without passing through the vapor tube 24; and also serves to prevent the heat from being deflected downwardly, but it reflects the heat and flame laterally to the fire box lining, hot water front or coils and upwardly to the top of the stove. The generator is subject to the application of the heat and flame throughout the area of the bottom wall and both the inlet passage 12 and the outlet passage 13 are also subject to the direct application of the heat and flame. Obviously this three-point application of the heat increases the generating efficiency and results in cleaner and better combustion. It also, because of the efficient design of the burner head, accelerates the generating process and reduces the tendency to formation of carbon deposit within the device.

50 Various other advantages of the device will be apparent to those skilled in the art without specific mention, and numerous variations in the construction and form of the parts may be made without departure from
55 the nature and principle of the invention.

I do not restrict myself in any unessential particulars, but what I claim and desire to secure by Letters Patent is:—

1. An oil burner comprising a generator, 60 means for admitting oil into said generator, a downwardly extending outlet passage from said generator, a tubular part having a restricted passage therethrough removably connected with said outlet passage and 65 having a closed outer end and having lateral

openings from said restricted passage, and a removable jacket forming a confined space around that portion of said tubular part having said lateral openings and being provided with an orifice opening laterally and of smaller area than said openings. 70

2. An oil burner comprising a generator, means for admitting oil into said generator, a downwardly extending outlet passage from said generator, a tubular part having a restricted passage therethrough removably connected with said outlet passage and having a closed outer end and having lateral openings from said restricted passage, a non-metallic jacket forming a confined space around that portion of said tubular part having said lateral openings and being provided with an orifice of smaller area than said openings, and means for securing said jacket on said tubular part in rigid relationship and impervious connection therewith. 75 80 85

3. An oil burner comprising a generator, and an outlet passage from said generator, in combination with a tubular part having a passage therethrough of less area than the area of said outlet passage and having a closed outer end, and a steatite jacket forming a confined space around a part of said tubular part which space is arranged to receive gas passing from said tubular part, said jacket having an outlet opening of less area than the passage through said tubular part and below said generator. 90 95

4. An oil burner comprising a generator, and an outlet passage from said generator, in combination with a tubular part having a passage therethrough of less area than the area of said outlet passage and having a closed outer end, a steatite jacket forming a confined space around a part of said tubular part which space is arranged to receive gas passing from said tubular part, said jacket having an outlet opening of less area than the passage through said tubular part and below said generator, and a vapor tube below said generator and above and surrounding the outlet opening from said jacket. 100 105 110

5. An oil burner comprising a tray arranged to contain a quantity of combustible liquid, a frame supporting said tray and having lateral air inlet openings in its sides and having its sides spaced from the sides of said tray and having a passage upwardly through one side, a pipe section extending from the upper end of said passage, a combined generator and flame spreader supported by the upper end of said pipe section above said tray, and a burner head supported by and in communication with said generator and flame spreader between said tray and said generator and spreader. 115
120
125

6. An oil burner comprising a tray arranged to contain a quantity of combustible liquid, a frame supporting said tray and 130

having lateral air inlet openings in its sides and having its sides spaced from the sides of said tray and having a passage upwardly through one side, a pipe section extending from the upper end of said passage, a combined generator and flame spreader supported by the upper end of said pipe section above said tray, a burner head supported by and in communication with said generator and flame spreader between said tray and said generator and spreader, a pair of detachable baffle plates, and means for supporting said baffle plates in connected relationship between said burner head and said generator and spreader.

7. An oil burner comprising a tray arranged to contain a quantity of combustible liquid, a frame supporting said tray and

having lateral air inlet openings in its sides and having its sides spaced from the sides of said tray and having a passage upwardly through one side, a pipe section extending from the upper end of said passage, a combined generator and flame spreader supported by the upper end of said pipe section above said tray, a burner head supported by and in communication with said generator and flame spreader between said tray and said generator and spreader, a pair of semi-tubular elements, and means supporting said semi-tubular elements in position to form a tube between said burner head and said generator and spreader and permitting removal of said elements while the remainder of the oil burner remains assembled.

SAMUEL T. DAVIDSON.
